UNITED STATES PATENT OFFICE.

ELMER E. MILLER, OF SACRAMENTO, PENNSYLVANIA.

TRIGGER MECHANISM AND SAFETY DEVICE THEREFOR.

1,356,779.

Specification of Letters Patent. Patented Oct. 26, 1920.

Application filed June 12, 1920. Serial No. 388,463.

To all whom it may concern:

Be it known that I, ELMER E. MILLER, a citizen of the United States, residing at Sacramento, in the county of Schuylkill and

5 State of Pennsylvania, have invented certain new and useful Improvements in Trigger Mechanism and Safety Devices Therefor, of which the following is a specification, reference being had to the accompanying drawings.

This invention relates to an improved trigger mechanism and safety device therefor for double barrel firing arms in general and particularly for shot guns, and an object is to provide a trigger mechanism which 15 is simple, efficient and practical in construction, and wherein only one trigger is employed for actuating the hammers of both barrels.

20 Another object is to provide an improved safety device for the single trigger of said mechanism to prevent operation of the trigger until it is desired to actuate the same, and in this case the safety device can be moved so that either one of the barrels may 25 be actuated.

Still another object is to provide a device 30 of this kind wherein provision of means is afforded for indicating whether the safety device is set at safety, or for firing either the right or the left barrel of the gun.

While the design and construction at present illustrated and set forth is deemed preferable, it is obvious that as a result of 35 a reduction of the invention to a more practical form for commercial purposes, the invention may be susceptible to changes, and the right to these changes is claimed, provided they are comprehended within the 40 scope of what is claimed.

The invention comprises further features and combination of parts, as will be herein-after set forth, shown in the drawings and claimed.

45 In the drawings:—

Figure 1 is a view in side elevation of the breech casing of a gun showing parts broken away showing the improved trigger mechanism as applied illustrating the safety device set to prevent the mechanism from being actuated for either the right or the left barrel,

Fig. 2 is a view in side elevation of a portion of the breech casing of the gun showing 50 the parts broken away and illustrating the

trigger mechanism in elevation, and showing the safety device as having been moved, whereby the trigger may be actuated for firing the left hand barrel,

Fig. 3 is a view in side elevation of a portion of the breech casing of the gun, showing the trigger mechanism in elevation, and illustrating the safety device as having been set, whereby the right hand barrel may be fired,

Fig. 4 is a transverse sectional view 60 through the trigger mechanism at a point in front of the swivel member, showing the position of said member after the right hand barrel has been fired,

Fig. 5 is a similar view showing the swivel member as having been completely actuated and the left hand barrel fired,

Fig. 6 is an enlarged detail perspective view of the trigger mechanism, showing the 75 safety device and the slide and slide plate showing the position of the safety device as having been actuated for firing the left hand barrel,

Fig. 7 is a detail view showing the swivel 80 member as set in safety position to prevent the trigger from being actuated and thereby preventing either one of the barrels from being fired,

Fig. 8 is a detail view showing the position of the swivel member slightly tilted to the right of one of the bevels 52 of the trigger so that the right hand barrel can be fired,

Fig. 9 is a detail view showing the position of the swivel member slightly to the left of one of the bevels 52 of the trigger so that the left hand barrel can be fired, and

Fig. 10 is a detail view of the slide plate.

Fig. 11 is a detail diagrammatic view 95 showing one position of the arm 23 in fact engaging the notch 28 of the weight 27,

Fig. 12 is a detail diagrammatic view showing the arm 23 engaging the notch 29 of the weight 27.

Referring to the drawings, 1 designates the breech casing of a double barrel firing arm, preferably of the shot gun type, and mounted in the casing are the right and left hammers 2 and 3. Also mounted in the casing are the right and left hammer retaining sears 4 and 5 which are under tension of the springs 4^a and 5^a.

Rising up from the lower part 7 of the breech casing is a swivel support on which

75

80

85

90

95

100

105

110

the sear operating swivel 8 is pivotally mounted as at 9. The sear operating swivel is provided with right and left hand arms 10 and 11 and the depending leg 13 of the 5 swivel is provided with a bifurcation 12. The right hand arm 10 of the sear operating swivel is provided with an aperture 14.

Pivotally mounted in the breech casing as at 16 is a trigger 15 which is provided with a 10 swivel retaining arm 17. For instance, the pivot of the sear operating swivel is not headed or swaged and in order to retain the sear operating swivel on the pivot 9, the arm 17 is provided in order to always retain 15 the swivel in position on the pivot. This arm 17 is disposed in a relatively close position to the swivel when the trigger is in its normal position, and when actuated, the upper part of the arm moves closer to the 20 swivel as it is obvious that when the trigger is actuated the swivel tends to move off its pivot, hence the provision of the arm 17, therefore, when the trigger is actuated and the upper part of the arm moves toward the 25 swivel, the arm will act to maintain the swivel on its pivot, in other words, will act to push the swivel back on the pivot.

The trigger 15 is provided with a rearwardly extending arm 18, which terminates 30 in an upwardly extending lug 19. A transverse pin 20 is mounted on the lug 19 and is provided with an enlargement 21 on one end. A support 22 is fixed in any suitable 35 manner upon the lower part of the breech casing and pivoted thereon as at 24 is an arm 23 which is provided with a slot 25, which receives the enlarged end of the pin 20.

It will be noted that when the trigger is pulled or actuated, the rearwardly extending 40 arm of the trigger will so move that the enlarged end 21 of the pin 20 will move in the slot 25 of the arm 23. Also mounted on the lower part of the breech casing is an upright 26 on which a detent weight 27 is pivoted. This weight is bifurcated in order to 45 straddle the upright 26 thereby more efficiently pivoting the weight at 26^a to the upright. The weight 27 is provided with upper and lower notches 28 and 29 either one 50 of which being adapted to be engaged by the free end of the arm 23.

A safety device 30 is pivoted at 48^a on the upright and also pivoted at 32 on the upright is a spring element 31. One arm 33 of the 55 spring element 31 engages the aperture 14 in the sear operating swivel while the other spring arm 34 of the element engages an opening 35 formed in an ear 36 of the safety device. The lower end 37 of the 60 safety device engages a notch 37^a of the lug 19 of the rearwardly extending arm 18 of the trigger. A slide 38 for actuating the safety device is provided. This slide operates in the slots 39 and 39^a, in other words is guided 65 in its movement forwardly and rearwardly.

One end of the slide projects entirely through the slot 39 and carries a slide plate 53. Extending transversely of the slide is a pin 40 and secured at 42 to the under part of the upper wall of the breech casing is a leaf 70 spring 41. The leaf spring is provided with a pair of arms 43 which straddle the slide. The arms 43 of the leaf spring are provided with a plurality of notches 44, 45 and 46 adapted to engage the opposite end portions 75 of the transverse pin 40, in order to hold the slide in safety position or in position for firing either the right or the left hand barrel of the gun. The slide 38 is provided with a depending lug 47 having a slot 48; and 49 80 denotes a pin carried by the upper end of the safety device and passing through the slot 48 thereby loosely pivoting the safety device to the leg of the slide so that when the slide is moved forwardly or rearwardly the safety 85 device may be actuated to neutral position or to either one of the firing positions.

A spring 50 is carried on the upright of the lower part of the breech casing and has one of its arms engaging the breech casing 90 and the other arm engaging the smaller end of the pin 20 acting to assist the trigger in its movement when actuated.

A roller 51 is carried by the sear operating swivel and is mounted between the arms 95 caused to be formed by the bifurcation 12. One edge of the trigger of that portion thereof which protrudes upwardly through the lower part of the casing and in advance of the arm 17 is provided with opposite 100 bevels 52 with either one of which the roller 51 engages.

The slide plate 53 has an upper knurled surface 54 which is designed to be engaged by the thumb of the operator in order to 105 adjust the slide forwardly or rearwardly in order to position the safety device neutral or in either one of the firing positions. The slide plate 53 has an opening 55 at one end and etched or otherwise applied 110 to the outer face of the breech casing are indications 56, 57 and 58. The indication 56 is indicated by the letter S while the indication 57 consists of the letter R which indicates that when the plate 53 is moved 115 rearwardly to expose the letter R the right hand barrel can be fired. The indication 58 consists of the letter L and when the slide plate is moved so that its opening 55 will expose the letter L it will signify that the 120 left hand barrel may be fired.

The operation of the trigger mechanism and safety device therefor is as follows:—

As shown in Fig. 1, the device is set for 125 holding the single trigger and preventing the same from being actuated. Under these circumstances the gun can be readily carried without fear of its accidentally firing.

As shown in Fig. 3 the safety device has been tilted to the rear in which case the 130

lower end of the device is disengaged from the notch 37^a on the lug 19. In this case the safety device is positioned so that the spring element 31 is disposed to cause pressure on the right hand arm 10 of the swivel, thereby disposing the roller 51 of the swivel to the right hand bevel of the edge of the trigger. In fact the roller 51 will be arranged sufficiently to the right of the edge 10 that when the trigger is actuated the right hand arm 10 of the swivel will engage and operate the right hand sear thereby releasing and permitting the right hand hammer to be actuated and the right hand barrel 15 fired.

The safety device may then be moved forwardly to a neutral position and then farther forward until the lower end of the safety device assumes a position to the rear 20 of the lug 19. The safety device in this position then tensions the spring element so that the spring element 33 bears sufficiently in the aperture 14 of the arm 10 of the swivel so as to tilt the depending lug 13 25 to the left of the edge of the trigger in engagement with the left hand bevel of the trigger. This operation will permit the swivel to be further tilted to the left of the left hand bevel of the edge of the trigger 30 and therefore cause the left hand arm 11 and swivel to bear upwardly on the left hand sear from releasing and permitting the left hand hammer to actuate and fire the left hand barrel as shown in Fig. 9.

35 While the safety device is set for firing the left hand hammer and left hand barrel, the gun is reloaded, and in this instance the left hand barrel may be fired first and the right hand barrel can be next fired. After 40 again reloading the gun the left of the swivel is set to the right of the edge of the trigger, the right hand barrel can again be fired first.

In Fig. 1, there is shown parts of the 45 trigger mechanism and in this view the hammers 2 are supposed to be cocked and in this case the arm 23 is in engagement with the lower end of the weight 27 and in this case the weight assumes the position shown. 50 These positions occur before the trigger is pulled. Also these positions occur when the sear operating swivel is set for operating the left hand sear and firing the left hand barrel. When the trigger is pulled and the 55 left hand barrel fired, the arm 23 moves upwardly so that its extremity will be in a position to be engaged by the upper notch 28 of the weight as in Fig. 11. When the trigger is pulled and the left hand barrel 60 fired, the weight oscillates forward thereby causing the upper notch 28 to engage the extremity of the arm 23 thereby holding it up, upon the rebound the weight oscillates backwardly and allows the arm 23 to oscillate 65 downward and to engage with the notch 29

as in Fig. 12 which will hold the sear operating swivel 8 from changing to a position for firing the second shot, that is as long as there is a pressure on the trigger. However, when the entire pressure on the 70 trigger is relieved, the tension on the sear operating swivel 8 will cause the swivel to change or oscillate to position its anti-frictional device to a position on the right hand side of the upper edge of the trigger in 75 which case the swivel is in a position for firing the right hand barrel. These operations of the several parts are repeated when the trigger is pulled for firing the right hand barrel. When the safety device is set 80 for firing the right hand barrel, these foregoing operations are repeated and then the left hand barrel may be fired. The sole purpose of the weight 27 is to prevent what is known as double firing, that is to say such 85 firing that will give the impression that only a single barrel has been fired. In further words, the firing of both barrels will be so close together that one cannot be distinguished from the other. Furthermore, the 90 weight 27 also prevents what is known as balking, that is to say, enables the swivel to change its position readily and thereby prevent balking.

In Fig. 11 a view is disclosed showing the 95 position of the arm 23 in engagement with the upper notch 28 showing the position of the weight at the time the trigger is pulled and at the time the weight 27 oscillates forward in engagement with the extremity of 100 the arm 23 so as to hold the arm 23 up. As before stated, as the pressure on the trigger is gradually released, the extremity of the arm 23 moves over the enlargement 27^a of the weight so as to engage the lower 105 notch 29 as in Fig. 12. This action occurs when the weight oscillates backwardly on the rebound. It is to be noted that at this point of the operation, pressure upon the trigger is not entirely released, therefore, 110 when the weight 27 again moves forward the extremity of the arm 23 will lie in the notch 29, and prevent the swivel from changing its position so that its anti-frictional device will engage on the right hand side of 115 the upper edge of the trigger. When the safety device is set at safety it pushes downwardly on the trigger and in this case the sear operating swivel is free to oscillate so that it can be set or oscillated to either 120 side of the upper edge of the trigger. After both barrels have been fired, the arm 23 moved to a downward position below the position it assumes when its extremity 125 is in engagement with the notch 29 and in this instance the extremity of the arm 23 will fall in the path of the lower end of the weight 27. It might be said that while the arm 23 is held in the lower notch 29 during the rebound from the shoulder, the 130

trigger will be tightened in the finger of the operator and thus bring the arm 23 again into engagement with the upper notch 28, but will not be held up a second time during the rebound pull and hence will fall down to a position adjacent the foot of the weight or rather the lower end of the weight.

As shown in the drawings, particularly in Fig. 3, the breech casing has a recess 39^a for the reception of a member 2^b. The usual breech lock 2^c is shown in dotted lines in Fig. 3 and the upper end of this breech lock has a shoulder 2^d. The member 2^b is mounted in the groove or slot 39^a in a position intermediate the end of the slide 38 and the shoulder 2^d of the breech lock, so that in case the breech of the gun is unlocked, and broken for the purpose of reloading, the lock when rotating will cause the member 2^b to move backward and operate the slide 38 thereby reseating the slide at safety hence preventing accidental operation of the trigger mechanism.

25 The invention having been set forth, what is claimed as new and useful is:—

1. In a trigger mechanism and lock therefor, a breech casing, right and left hammers mounted therein, spring tensioned sears 30 for retaining the hammers in cocked positions, a fulcrumed swivel positioned to engage on either side of a trigger for actuating either of said sears, and a single trigger for actuating the swivel to fire first one 35 and then the other of said hammers.

2. In a trigger mechanism and lock therefor, a breech casing, right and left hammers mounted therein, spring tensioned sears for retaining the hammers in 40 cocked positions, a fulcrumed swivel positioned to engage on either side of a trigger for actuating either of said sears, and a single trigger for actuating the swivel to fire first one and then the other of said 45 hammers, and means for tensioning the swivel, whereby it may operate on either side of the trigger.

3. In a trigger mechanism and lock therefor, a breech casing, right and left 50 hammers mounted therein, spring tensioned sears for retaining the hammers in cocked positions, a fulcrumed swivel positioned to engage on either side of a trigger for actuating either of said sears, and a single 55 trigger for actuating the swivel to fire first one and then the other of said hammers, means for tensioning the swivel, whereby it may operate on either side of the trigger, and means to be disposed in a neutral 60 position for engagement with a part of the trigger for preventing movement thereof, and holding the swivel centrally of the trigger, thereby preventing the trigger from being accidentally actuated.

65 4. In a trigger mechanism and lock there-

for, a breech casing, right and left hammers mounted therein, spring tensioned sears for retaining the hammers in proper positions, a single trigger mounted in the breech casing, a swivel member pivotally mounted 70 in the casing for positioning a part thereof on either side of the trigger, whereby upon the actuation of the trigger the swivel member may actuate one or the other of said sears for releasing and permitting one of 75 the hammers to operate.

5. In a trigger mechanism and lock therefor, a breech casing, right and left hammers mounted therein, spring tensioned sears for retaining the hammers in proper positions, 80 a single trigger mounted in the breech casing, a swivel member pivotally mounted in the casing for positioning a part thereof on either side of the trigger, whereby upon the actuation of the trigger the swivel member 85 may actuate one or the other of said sears for releasing and permitting one of the hammers to operate, and means for setting the swivel member in position relatively to either side of the trigger. 90

6. In a trigger mechanism and lock therefor, a breech casing, right and left hammers mounted therein, spring tensioned sears for retaining the hammers in proper positions, a single trigger mounted in the breech casing, a swivel member pivotally mounted in the casing for positioning a part thereof on either side of the trigger, whereby upon the actuation of the trigger the swivel member may actuate one or the other of said sears 100 for releasing and permitting one of the hammers to operate, means for setting the swivel member in position relatively to either side of the trigger, and a safety device to be either actuated to engage and hold 105 the trigger from being operated, or actuated for causing said setting means to set the swivel member to either side of the trigger.

7. In a trigger mechanism and lock therefor, a breech casing, right and left hammers mounted therein, spring tensioned sears for retaining the hammers in proper positions, a single trigger mounted in the breech casing, a swivel member pivotally mounted in the casing for positioning a part 110 thereof on either side of the trigger, whereby upon the actuation of the trigger the swivel member may actuate one or the other of said sears for releasing and permitting one of the hammers to operate, means for 115 setting the swivel member in position relatively to either side of the trigger, and a safety device to be either actuated to engage and hold the trigger from being operated, or actuated for causing said setting means 120 to set the swivel member to either side of the trigger, and means for adjusting the safety device to neutral position or to position for firing either one of the barrels of 125 the gun. 130

8. In a trigger mechanism and lock therefor, a breech casing, right and left hammers mounted therein, spring tensioned sears for retaining the hammers in proper positions, 5 a single trigger mounted in the breech casing, a swivel member pivotally mounted in the casing for positioning a part thereof on either side of the trigger, whereby upon the actuation of the trigger the 10 swivel member may actuate one or the other of said sears for releasing and permitting one of the hammers to operate, means for setting the swivel member in position relatively to either side of the trigger, 15 and a safety device to be either actuated to engage and hold the trigger from being operated, or actuated for causing said setting means to set the swivel member to either side of the trigger, means for adjusting the safety device to neutral position or 20 to position for firing either one of the barrels of the gun, and means for holding the adjusting means in different adjusted positions, and means for indicating whether or 25 not the safety device is set for neutral or for firing either one of the barrels of the gun.

9. In a trigger mechanism and lock therefor for double barrel firing arms, a breech casing, right and left hammers mounted in 30 said casing for said barrels, a single trigger operating means for permitting one or the other of the hammers to actuate, said means including a single trigger and a member pivotally mounted in the casing for position 35 on either side of the trigger, said member having an antifrictional device coöperating with the trigger to permit freedom of movement thereof, a safety lever for locking the trigger in neutral position, and means 40 adapted to be put under tension by the safety lever for moving a part of the swivel member to either side of the trigger, whereby the swivel member may actuate its mechanism for releasing either one of the 45 hammers.

10. In a trigger mechanism and lock therefor for double barrel firing arms, a breech casing, right and left hammers mounted in said casing for said barrels, a 50 single trigger operating means for permitting one or the other of the hammers to actuate, said means including a single trigger and a member pivotally mounted in the casing for position on either side of the trigger, 55 said member having an antifrictional device coöperating with the trigger to permit freedom of movement thereof, a safety lever for locking the trigger in neutral position, and means adapted to be put under 60 tension by the safety lever for moving a part of the swivel member to either side of the trigger, whereby the swivel member may actuate its mechanism for releasing either of the hammers, a slide for adjusting 65 the safety lever to neutral locked position

with the trigger, or in a position to actuate the swivel member to either side of the trigger.

11. In a trigger mechanism and lock therefor for double barrel firing arms, a 70 breech casing, right and left hammers mounted in said casing for said barrels, a single trigger operating means for permitting one or the other of the hammers to actuate, said means including a single trigger 75 and a member pivotally mounted in the casing for position on either side of the trigger, said member having an antifrictional device coöperating with the trigger to permit freedom of movement thereof, a safety lever for 80 locking the trigger in neutral position, and means adapted to be put under tension by the safety lever for moving a part of the swivel member to either side of the trigger, whereby the swivel member may actuate its 85 mechanism for releasing either of the hammers, a slide for adjusting the safety lever to a neutral locked position with the trigger, or in a position to actuate the swivel member to either side of the trigger, and means 90 for holding the slide in different adjusted positions.

12. In a trigger mechanism and lock therefor for double barrel firing arms, a breech casing, right and left hammers 95 mounted in said casing for said barrels, a single trigger operating means for permitting one or the other of the hammers to actuate, said means including a single trigger and a member pivotally mounted in the casing 100 for position on either side of the trigger, said member having an antifrictional device coöperating with the trigger to permit freedom of movement thereof, a safety lever for locking the trigger in neutral position, 105 means adapted to be put under tension by the safety lever for moving a part of the swivel member to either side of the trigger, whereby the swivel member may actuate its mechanism for releasing either of the 110 hammers, a slide for adjusting the safety lever to a neutral position with the trigger, or in a position to actuate the swivel member to either side of the trigger, and means for holding the slide in different adjusted positions, 115 and means for indicating whether the slide is in neutral, or in position indicating whether or not the trigger may actuate the swivel member for either the right or the left hand barrel.

13. In a trigger mechanism and lock therefor, operating sears, a swivel for actuating either sear, a trigger therefor, and loosely mounted means oscillatable forwardly upon a pull on the trigger and the 125 jar of the gun and oscillatable backwardly upon the rebound and being coöperatively connected with the swivel acting to prevent the swivel from changing its position relatively to the trigger until pressure is re- 130

lied on the trigger thereby preventing double firing.

14. In a trigger mechanism, hammer operating sears, a swivel for operating either 5 one of the sears, a trigger coöperating with the swivel for actuating either sear, a pivoted member, and loosely mounted means operated by the trigger to a position in the path of said pivoted member, which, upon 10 the pull of the trigger and the jar of the gun oscillates forward in engagement with said means and upon the rebound and the reliefment of pressure on the trigger oscillates backwardly, whereby double firing is 15 prevented.

15. In a trigger mechanism, hammer operating sears, a swivel for operating either one of the sears, a trigger coöperating with the swivel for actuating either sear, a pivoted 20 member, and loosely mounted means operated by the trigger to a position in the path of said pivoted member, which upon the pull of the trigger and the jar of the gun oscillates forward in engagement with 25 said means and upon the rebound oscillates backwardly, said pivoted member having means to be engaged by the trigger actuated means so that when the trigger tightens in the finger of the operator, the swivel is prevented 30 from oscillating to the other side of the trigger thereby preventing double firing.

16. In a trigger mechanism, hammer operating sears, a swivel to actuate either one of the sears, a trigger for the swivel, a pivoted 35 member loosely movable caused by the rebound and forward movement of the gun, an oscillatory arm adapted to be actuated by the trigger when the swivel is actuated so that when the trigger is pulled the member 40 oscillates forward and is provided with means engaging the extremity of the arm to hold the same up, said pivoted member upon the rebound and when pressure on the trigger is partially relieved adapted to oscillate backward, said member 45 at its lower portion being engaged by the extremity of the arm, while partial pressure is still urged on the trigger thereby preventing the swivel from changing its position relatively to the trigger on the other side thereof and thereby preventing double 50 firing.

trigger on the other side thereof and there- 50 by prevent double firing.

17. In a trigger mechanism, hammer operating sears, a swivel to actuate either one of the sears, a trigger for the swivel, a pivoted member, an oscillatory arm adapted to 55 be actuated by the trigger when the swivel is actuated so that when the trigger is pulled the member oscillates forward and is provided with means engaging the extremity of the arm to hold the same up, said pivoted 60 member upon the rebound and when pressure on the trigger is partially relieved adapted to oscillate backward, said member at its lower portion being engaged by the extremity of the arm, while partial pressure is still urged on the trigger thereby preventing the swivel from changing its position relatively to the trigger on the other side thereof and thereby preventing double 65 firing, and means for setting the swivel 70 relatively to the trigger.

18. In a trigger mechanism, hammer operating sears, a swivel to actuate either one of the sears, a trigger for the swivel, a pivoted member, an oscillatory arm adapted to 75 be actuated by the trigger when the swivel is actuated so that when the trigger is pulled the member oscillates forward and is provided with means engaging the extremity of the arm to hold the same up, said pivoted 80 member upon the rebound and when pressure on the trigger is partially relieved adapted to oscillate backward, said member at its lower portion being engaged by the extremity of the arm, while partial pressure is still urged on the trigger thereby preventing the swivel from changing its position relatively to the trigger on the other side thereof and thereby preventing double 85 firing, and means for setting the swivel relatively to the trigger, and means actuated by the breech lock of the gun for returning the 90 swivel setting means from its position indicating the left hand barrel to its neutral or safety position.

95 In testimony whereof I hereunto affix my signature.

ELMER E. MILLER.
